PERPETUAL CALENDAR

John A. Vierling, St. Paul, Minn., assignor to Standard
Packaging Corporation, New York, N.Y., a corporation
of Virginia

Filed Sept. 1, 1961, Ser. No. 66,720

Term of patent 14 years

(Cl. D74—5)

FIG. 1

FIG. 2

FIG. 3

FIGURE 1 is a front perspective view of a perpetual calendar, showing my new design;

FIGURE 2 is a side perspective view thereof; and

FIGURE 3 is a rear perspective view thereof.

The essential features of my design reside in the portions shown in solid lines on the drawing.

I claim:

The ornamental design for a perpetual calendar, as shown and described.
